HEEL INSERT

William A. Evans, New York, N. Y., assignor of
one-half to Harry Victor Morley and William L.
Morris, New York, N. Y.

Application December 7, 1933, Serial No. 701,258

3 Claims. (Cl. 36—75)

The present invention relates to cushioned heels for foot-wear. More particularly, the invention relates to heels of this type, which are designed to be of non-slip and wear-resistant material.

The rubber, cork and other materials of which such heels have heretofore been composed are all notoriously non-resistant to wear, and are unreliable, as to tread, on wet ground, particularly when rounded off by wear.

It is a primary object of the invention to provide a cushion heel in which there cannot be that rounding off by wear, which has heretofore been characteristic of such heels. It is, however, a further object of the invention to provide a cushion heel which is non-slip regardless of the question of wear thereof.

Any attempt to make a cushion heel resistant to wear and slip, as by having nails or spikes set therethrough to the last or body of the shoe, must fail; because rigid nails or spikes set to a hard base at the plane of the wearer's foot must render nugatory the cushioning material. In certain instances, on the other hand, plates, tabs, or gadgets of various kinds have been pressed or stamped into a cushion tread, with the idea that these would stay any wear of the cushioning material in which they were set, or would resist any slipping tendency of the heel on wet ground. In all such attempts, however, to combine, by use of metal inserts in rubber heels, the benefits of wear-resistance and resiliency, it has been found that the wear-resistant elements either impair the resiliency of the heel, or soon drop from, or tear, the shoe-tread.

As distinguished, on the one hand, from a wear-resistant or non-slip device extending through the cushion to a seat on the last or body of the shoe, such as would nullify the cushion, and, on the other hand, from a device so ineffectively anchored and seated as to become free to shift in, or fall out of the heel, a feature of the present invention is a ground-contact gadget which rides on the cushioning element of the heel, and is so seated and anchored therein as to be held against displacement in any direction.

It is a feature of the invention that the heel may consist of an inner or cushioning lift of relatively soft and resilient material, and an outer or tread lift of harder and better wear-resisting material; or the heel may be made as a unit of resilient material, uniform throughout. In the first instance, the surface of the inner or cushion lift may conveniently serve as the seat for the gadgets mentioned above; and the latter be so flanged or laterally expanded in dove-tail or other formation,

in or below the tread lift, as to preclude outward movement of the gadget through the tread-lift, away from the face of its seat on the cushion lift. To accommodate such flange or lateral expansion of the gadget, the inner face of the tread-lift may be countersunk.

When the heel is a unit of rubber or other resilient material, the gadgets may be set into the material, to the proper, limited, depth, with one face at the tread surface, before the material has set or hardened; so that, upon hardening of the material, and by reason of the flanged or laterally expanded base of the gadget, the gadget is held interlocked with the rubber, against displacement.

To provide against shift or displacement of the gadget toward or through the side or periphery of the heel, the gadget is preferably of dart shape, or laterally shouldered formation.

A feature of the invention, in the preferred form thereof, is a tread of cushion material, cut-away centrally thereof to a depth of say one heel lift, or so molded, as to present a ground-contact or wearing surface of U or horseshoe formation. This cut-out in the tread is shown in the accompanying drawing as having its peripheral walls tapered laterally outward from the bottom of the cut to the face of the tread; so as to make the cut of arch-shaped cross-section; whereby, as the ball of the foot heel exerts its pressure centrally of the shoe heel, the arch of the cut is slightly flattened, and the sides or walls thereof spread apart to cause the edges of the cut, at the inner horseshoe, to bite the ground on opposite sides of the heel, with a double grip, to assist in resisting slip in any direction. This yield of the arch, furthermore, adds appreciably to the spring or resiliency of the heel; and the cut makes the heel lighter, and walking better on uneven ground.

The reduction of tread surface to U or horseshoe formation is the more readily permissible in my heel, because the tread surface, which in other heels could not be spared except at the expense of rapid wear, is here unnecessary, due to the presence on the horse-shoe tread of my heel, of one or more of the wear-resistant gadgets heretofore mentioned. The feature of the horse-shoe tread, however, may be employed, in certain instances, where the gadgets are absent.

Other objects and features of the invention will more fully appear upon reference to the accompanying drawing, in which:

Fig. 1 is a view in perspective of an assembled heel embodying the invention in the preferred construction thereof.

Fig. 2 is a view in perspective of the wear-resistant device, in the preferred form thereof.

Fig. 3 is a view in side elevation of the device shown in Fig. 2.

5 Fig. 4 is a plan view of the bottom, or outer face, of a part of the outer lift of the heel, showing the hole or seat for the Fig. 2 device.

10 Fig. 5 is a plan view of the Fig. 4 heel-piece or lift, showing the same hole or seat for the Fig. 2 device, viewed from the inside.

Fig. 6 is a view in cross-section, taken on the line 6—6 of Fig. 5.

15 Fig. 7 is a view in perspective of a broken part of an assembled heel embodying the invention in another modification thereof.

Fig. 8 is a view in perspective of the wear-resistant device of Fig. 7.

20 Fig. 9 is a diagrammatic outline to show the gripping action of the Fig. 1 form of tread upon application of pressure by the ball of the wearer's heel.

25 Referring to the drawing, the heel is shown as comprising a cushioning lift 10, preferably of relatively soft rubber. An outer lift, or tread, 11, which is shown as of U or horse-shoe shape, and which may be of the same, or of other and harder material than the lift 10, but which, like the lift 10, is preferably of rubber, is secured to the outer face of the lift 10, and with the lift 10, to the 30 shoe body or last by spikes or pins 12, set in the holes 13, which register in the two lifts, to be continuous therethrough. A $\frac{3}{8}$ " cushion 10 and a $\frac{1}{4}$ " tread will be found satisfactory for men's shoes of the ordinary kind.

35 Referring now more particularly to the wear-resistant device or gadget 9 shown in Fig. 2, the same is shown as comprising a blunted dart-shaped lug 14, the base of which in Fig. 1 is shown near the edge or periphery of the heel, and the other end of which is bellied out in post-like formation to provide shoulders 15, which, with the shoulders 16 of the dart, prevent outward longitudinal movement, or radial displacement of the device in the body of the tread 11. 40

45 The cut in the tread 11, to receive this dart-shaped lug 14, is shown in the bottom-face view of the tread in Fig. 4.

50 To prevent the device of Fig. 2 from dropping out of the tread, and from displacement at an angle to the face of the tread, the device of Fig. 2 is provided with a flange or plate 17, which may conveniently be a continuation of the dart formation of the lug 14 at the base thereof, rounded toward the center of the heel co-axially with the post of the lug. This lateral expansion of the device in the flange 17 has the further function of assisting the shoulders 15 and 16 in holding the device as a whole against radial displacement. In order that the flange 17 may not 55 interfere with proper seating of the lifts, one on the other, the inside face of the tread, see Figs. 5 and 6, is countersunk at 18 to receive the flange and hold the same flush with the face of the tread. Although in Fig. 1 I have shown the heel 60 as having one of the gadgets therein, it will be obvious that two, or more than two, may be employed, as desired.

65 In another form of the invention, the pieces 10 and 11 may be molded as a single piece; in 70 which event the wear-resistant devices, or gadgets, will be set into the rubber, or into the casting die, before the rubber has hardened, or before the casting operation; so that, upon hardening of the rubber, the gadgets will be locked by the 75 rubber, by means of the shoulders, flanges, or

other interlocking elements of the gadgets, against displacement in any direction.

It has been pointed out that in the Fig. 1 construction the tread lift is of U or horse-shoe shape, to afford a central opening therethrough; the sides or walls of which are tapered laterally outward from the bottom of the cut to the face of the tread. This opening or cut, with its consequent lightness of tread material, may be of other shape, or may be entirely absent in embodiments of the invention where the anti-slip feature is not desired. The reduced wearing area of the tread due to the opening 19 is compensated for by the superior wearing qualities of the gadgets 14. 10 15

The opening 19, when present, however, and as hereinbefore stated, introduces a feature of the invention which may add greatly to the ground-gripping, or non-slip, character of the device as a whole, as well as the the resiliency or 20 spring thereof. In Fig. 9, the weight of the body on the ball of the heel of the foot, as applied to the center of the shoe-heel, is indicated as to position by the arrow 20. This pressure somewhat flattens the arch of the cut-out, to cause the tread 25 to bite the ground, with a double grip, at the edges 21 and 22 of the cut, on opposite sides of the heel, as well as to the rear thereof. Moreover, in so far as the edge at one side of the cut 19 tends to resist slip in one direction, the edge 30 at the other side tends to resist slip in the other direction,—as indicated by the Fig. 9 diagram.

35 In Figs. 7 and 8, is shown a form 23 of the wear-resistant device or gadget, in which the flange of the Fig. 2 device is lacking; but in substitution for which flange, the gadget 23 is shown as having its periphery 24 flared and expanded outwardly and laterally in the heel, in dove-tail form, to prevent loss of the gadget, or displacement thereof vertically outward with respect to 40 the tread face. The heel tread, (in this instance not shown in the drawing), is countersunk to the dove-tail form of the gadget 23, to interlock with and hold the latter. Here again, however, the heel may be of one piece, and the gadget set into the material thereof, before the rubber has set or hardened; so that, the pocket for the gadget 23 45 may be formed in the molding of the rubber against the gadget. 50

I claim:

1. A heel for shoes, comprising a tread lift and an inner cushioning lift of rubber or other resilient material, the tread lift having a passage therethrough from face to face, and a wear-resistant element in said passage having a hard wearing face at the tread of the heel, and having a seat on the inner lift for yield therewith with respect to the foot-supporting shoe-surface to which the heel attaches, the wear-resistant element, behind the tread surface, having an integral lateral expansion or offset interlocking with the heel material to prevent outward displacement of the wear-resistant element, and one of said lifts having a countersink or recess of size and shape to accommodate said lateral expansion or offset on the wear-resistant element. 60 65

2. A heel for shoes comprising a tread layer having a recess therein, a wear-resistant element in said recess shaped to permit insertion there- 70 of into the recess after the recess has been made and having a hard outer face thereof at the tread surface of the heel for ground contact, a thickness of cushioning material closing the inner end of the recess and against which the wear-re- 75

sistant element is seated to have yield or play with respect to the foot-supporting shoe-surface to which the heel attaches, and means integral with said wear-resistant element to yield therewith for interlockment with the tread layer to hold the wear-resistant element against outward displacement.

3. A heel for shoes, comprising a tread lift and an inner cushioning lift of rubber or other resilient material, the tread lift having a passage therethrough from face to face, and a wear-resistant element shaped for insertion into said passage from the interior face of the tread lift

when the lifts are separated; the wear-resistant element when in place having a metal or hard wear-resistant, ground contact surface at the tread of the heel, and having a seat on the inner lift for yield therewith with respect to the foot-supporting shoe-surface to which the heel attaches, and having behind the tread surface of the heel a lateral offset for holding the wear-resistant element against outward displacement, said offset being integral with the body of the wear-resistant element to participate in said yield of the latter.

WILLIAM A. EVANS.
